UNITED STATES PATENT OFFICE

147,236

DESIGN FOR A LEATHER JACKET

Jack Greenberg and Benjamin Fortgang,
New York, N. Y.

Application January 23, 1947, Serial No. 136,326

Term of patent 7 years

(Cl. D3—4)

To all whom it may concern:

Be it known that we, Benjamin Fortgang and Jack Greenberg, both citizens of the United States of America, residing at New York city, county of New York, and State of New York, have invented a new, original, and ornamental Design for a Leather Jacket, of which the following is a specification, reference being had to the accompanying drawing, forming part thereof, wherein,

We claim:

The ornamental design for a leather jacket, substantially as shown.

JACK GREENBERG.
BENJAMIN FORTGANG.
